UNITED STATES PATENT OFFICE

JOSEPH M. MAJEWSKI, JR., OF KANSAS CITY, MISSOURI

DESIGN FOR A TABLET

Application filed October 13, 1930. Serial No. 37,255. Term of patent 3½ years.

To all whom it may concern:

Be it known that I, JOSEPH M. MAJEWSKI, Jr., a citizen of the United States, residing at Kansas City, in the county of Jackson, and State of Missouri, have invented a new, original, and ornamental Design for a Tablet of which the following is a specification, reference being had to the accompanying drawings, forming a part thereof.

The drawings show only a fragmentary portion of the surface ornamentation, the complement being understood to be merely a continuation thereof.

I claim:

The ornamental design for a tablet or similar article as shown and described.

JOSEPH M. MAJEWSKI, JR.
